Int. Cl. D21—01

U.S. Cl. D34—5 TT

Fig. 1.

The figure is a top plan view of a cribbage game board showing my new design, characterized in that each of the four generally oval game board lanes, within which peg receiving holes are arranged, is of a different color, the color of each lane corresponding to the color of the central portion of one of the four corner disposed numbered circles.

The game board bearing my new design is of conventional thickness.

I claim:

The ornamental design for a cribbage game board, as shown and described.
